UNITED STATES PATENT OFFICE.

GEORGE WESTINGHOUSE, OF PITTSBURG, PENNSYLVANIA, ASSIGNOR TO THE WESTINGHOUSE MACHINE COMPANY, A CORPORATION OF PENNSYLVANIA.

ELASTIC-FLUID TURBINE.

935,286.

Specification of Letters Patent. Patented Sept. 28, 1909.

Application filed September 27, 1904. Serial No. 226,130.

To all whom it may concern:

Be it known that I, GEORGE WESTINGHOUSE, a citizen of the United States, and a resident of Pittsburg, in the county of Allegheny and State of Pennsylvania, have invented a new and useful Improvement in Elastic-Fluid Turbines, of which the following is a specification.

This invention relates to elastic fluid turbines, and as an object has the production of a turbine simple and compact of structure and extremely efficient in its utilization of the motive fluid.

A further object has been to produce a turbine in which substantially all of the fluid expansion occurs within rotatable agents.

A still further object has been to provide means in a turbine whereby the harmful effects (such harmful effects relate entirely to efficiency) due to fluid leakage between the rotor and stator are reduced to the minimum.

These as well as many other objects readily appearing to one skilled in the art, are attained in the turbine structure described in this specification and illustrated in the accompanying drawings throughout which similar elements are denoted by like characters.

As the stator as well as the rotor of a turbine embodying this invention may be of any desired design and as this invention relates principally to the fluid working agents a complete turbine is not illustrated.

In the drawings Figure 1 is a sectional view of a portion of a turbine embodying this invention: Fig. 2 is a sectional view taken on line A—A in Fig. 1: Fig. 3 is a developed section taken on lines B—B in Figs. 1 and 2: Fig. 4 is a view similar to Fig. 1, illustrating a modified form of this invention: Fig. 5 is a view taken on line C—C in Fig. 4: Figs. 6 and 7 are views similar to Figs. 4 and 5 and illustrate another modification of this invention: Fig. 8 is a partial sectional view through the nozzles 8 and blades 9 at right angles to the plane of Fig. 1.

In all forms of this invention the fluid utilizing agents on the rotor are formed so that the motive fluid in its course there-through produces a three-fold effect, that is to say, on entering said agents the fluid delivers up a certain portion of its energy to

the rotor; the fluid jet is then deflected, thereby delivering another portion of its energy and, passing a throat, it expands so that its speed is raised and it finally leaves the agents acting by reaction to deliver up a further portion of its energy. It is essential that the throat mentioned be arranged well behind the center of deflection so that no expansion takes place until after the fluid stream has been reversed in direction whereby all the reactive effect due to expansion acts in the direction of rotation of the rotor.

From Figs. 1, 4 and 6 it will be seen that the construction illustrated contemplates a double flow turbine, but it will be understood that this invention is equally applicable to a single flow turbine, and that when so applied any of the well-known means for counteracting the longitudinal thrust of the rotor may be utilized, and this invention therefore is not limited to either a single or double flow machine. Neither is it limited to a parallel flow turbine, but may be applied in modified forms to radial as well as parallel flow, either inward or outward.

The motive fluid which hereafter for the sake of clearness will be called steam, although this invention is not limited to the use of steam since any other suitable elastic fluid may be utilized, enters the steam space through expansion nozzles 8. These expansion nozzles 8 may be as many in number as desired and may lead from an annular steam channel (not shown) extending around the turbine and may be arranged in pairs or sets of any number and may either be divergent or not as is necessary.

The steam issuing from the nozzles 8 impinges on an annular set of blades 9 carried by the rotor and which are adapted to absorb all of the velocity of the steam issuing from said nozzles. The steam issuing from impulse blades 9 is collected in a steam chamber 10 and issues therefrom in both directions through reaction nozzles 11. Reaction nozzles 11 provided with a contracted throat 12 are preferably of the form illustrated in Fig. 3 and are obliquely disposed to the axis of the rotor whereby the maximum reactive effect is secured.

The angularity of the steam jet issuing from nozzles 11 is changed by means of stationary guide vanes 13 fixed to the casing,

and the fluid spaces between said guide vanes, which are arranged in an annular row around the stator, are preferably of equal area from their inlets to their outlets providing an unrestricted gradual change in direction. The steam issuing from the passages between the guide vanes 13 enters a row of reaction nozzles 14 each of which is provided with a contracted throat as illustrated in Fig. 1 and of an area sufficiently greater than the area of nozzles 11 to provide for the expanded steam.

The steam on issuing from nozzles 14 has its angularity changed by means of fixed vanes 15 similar to vanes 13 but of greater length whereby an increased steam space over the spaces between blades 13 is secured.

On issuing from between blades 15 the steam enters another row of reaction nozzles 16 similar to nozzles 14 but of sufficiently greater area to accommodate the expansion.

After issuing from nozzles 16 the angularity of the steam is again changed by a row 17 of guide vanes and from said guide vanes it will be passed to the exhaust end of the turbine through a suitable number of rows of moving and stationary blades and vanes whereby its remaining pressure and velocity are fractionally expanded and the energy so obtained applied to the rotor.

As many rows of reaction nozzles and guide vanes as are desired to secure the desired pressure drops may be employed, and this invention is not limited to any certain number of such reaction nozzles and guide vanes, nor to any certain number of impact and reaction blades and vanes, which impact and reaction blades and vanes will be similar to the blading of the "Parsons" type of turbine.

Located exteriorly to each row of reaction nozzles and between the shroud 18 thereof and the stator casing an interleaving seal 19 is provided, and each of said seals is preferably divided and provided with a steam channel 20 which leads from a point between any two of the leaves of said seal to a point of the reaction nozzle whereby the steam which passes the first series of leaves will enter the reaction nozzles and do work by reaction.

The rotary portion of the turbine may be formed of two similar cylinders 21 separated by a key-ring 22 which forms the inner wall of the rotary annular chamber 10 and said cylinders and key-ring are preferably secured together by a suitable number of bolts 23. Each cylinder 21 is formed with an undercut groove which receives a ring 24 in which the reaction nozzles are formed, and key-ring 22 is provided with a surface 32 which overlaps said ring 24.

Nozzle ring 24 is formed with annular flanges in the edges of which transverse grooves are formed of the shape it is desired

to give respectively to the sides and inner walls of the reaction nozzles. The parts of the metal left remaining as shown at 25 (Fig. 2) form the side walls of the nozzles and the outer walls or shrouds are formed by annular rings, or ring segments, secured to side walls 25; the ends 26 of said side walls project through said rings and are riveted over as shown in Fig. 2.

The shrouding ring for nozzles 11 forms the outer wall of the annular steam chamber 10 and also carries the set of impulse blades 9 through which the steam enters the annular chamber 10.

The shrouding rings for the nozzles are shaped on their inner peripheries to form the outer surface of the nozzles and the contracted throats therefor.

Where the series of nozzles is not continuous throughout the entire circumference of the rotor the construction illustrated in Figs. 4 and 5 may be utilized, and in this construction the rotor need only consist of two parts as shown in Fig. 4 and each of said parts provided in its respective periphery at places where the nozzles are required, with undercut slots 26 into which nozzle blocks or segments 27 are slipped. These blocks are provided with slots, milled or otherwise formed, to the shape of the outer and side walls of the nozzles and the bottom of the slot or groove 26 is suitably shaped so as to form the inner walls of said nozzles. The blocks are further secured against displacement by centrifugal force by means of rings 28 which may, if desired, be shrunk on.

In Figs. 6 and 7 a modified construction of the nozzles is shown in which the nozzles are formed by slots milled out of blocks 29 similar to blocks 27, but in place of cutting the slots from the inner periphery of the blocks they are formed at the outer periphery, and the boundary of the nozzles is formed by shrink rings 30. Blocks 29 are preferably dovetailed or wedge-shaped in two parts, that is to say, the dovetail faces of the block slightly converge, as indicated by dotted lines 31 Fig. 7, in the direction of flow of the motive fluid whereby the pressure of said fluid tends to tighten the blocks in their respective grooves.

The number of slots and blocks will of course depend upon the number of groups of nozzles desired and the method of constructing the groups of nozzles is not restricted to turbines constructed in the manner hereinbefore described but is applicable to turbines of other constructions.

It will be understood, although the nozzles are shown contracted to a throat both radially and circumferentially the whole of the contraction may take place circumferentially so that the outer and inner walls of the nozzles are parallel to one another, in which case complete rings may be employed

in place of the segments indicated in Figs. 2 and 7 for forming the outer boundaries of the nozzles.

Having thus described this invention, 5 its construction and modified forms thereof, as well as its mode of operation, what I claim as new and useful and desire to secure by Letters Patent is:—

1. In an elastic fluid turbine, agents where- 10 in the motive fluid in its course therethrough gives up a portion of its energy first by impact, then on being deflected, by impulse, and finally after reduction in pressure and increase of speed, by reaction.

15 2. In an elastic fluid turbine, a plurality of rows of moving agents whereby the fluid pressure is converted into velocity and said velocity abstracted, and a plurality of rows of stationary agents alternating with said 20 rows of moving agents, whereby without creating pressure drops the angularity of the fluid stream is changed.

3. In an elastic fluid turbine, nozzles whereby a portion of the fluid pressure is converted into velocity, a row of movable members absorbing such velocity, a rotatable collecting chamber for the motive fluid issuing from said members, instrumentalities whereby the fluid issuing from said collecting 30 chamber has a portion of its pressure converted into velocity and abstracted and a plurality of rows of moving blades and stationary vanes whereby the fluid, after having its velocity abstracted, is fractionally expanded and converted into rotary motion.

4. In an elastic fluid turbine, an expansion nozzle, a row of movable impulse blades absorbing the velocity of the fluid issuing from said nozzles, a rotatable fluid collecting 40 chamber receiving the fluid from said impulse blades and an interleaving seal adjacent to said impulse blades between the turbine rotor and stator.

5. In an elastic fluid turbine, a rotor provided with an undercut groove or channel, a nozzle block fitting said groove and a ring shrunk onto said rotor whereby said nozzle block is held against upward movement.

6. In an elastic fluid turbine, a turbine 50 rotor comprising two cylindrically formed members each fitting an undercut groove or channel in its periphery, a key-ring between said members provided with a portion overlying a portion of each of said channels, and a ring comprising fluid working agents in each of said channels and held against movement by the portions which overlie said channels.

7. In an elastic fluid turbine, in combina- 60 tion with its stator containing nozzles whereby a portion of the thermal energy of the entering working fluid is converted into kinetic energy in the form of velocity, a rotor, impulse blades carried by the rotor whereby the energy due to said velocity is absorbed,

a chamber communicating with the outlets of said blades and forming a connecting chamber wherein no expansion of the motive fluid therein occurs, and reaction nozzles on the rotor fed from said chamber.

70

8. In an elastic fluid turbine, a rotor provided with rows of reaction nozzles, a casing provided with rows of stationary vanes, a shroud for each row of nozzles, an interleaving seal between said shroud and the 75 inner face of said casing, fluid passages between said seal and said nozzles whereby fluid leaking into said seal is discharged into said nozzles.

9. In an elastic fluid turbine, a casing, a 80 rotor provided with reaction nozzles, fluid seals between said rotor and said casing and means for discharging fluid entering said seals into said nozzles.

10. In an elastic fluid turbine, a casing, a 85 rotor provided with a reaction nozzle, a fluid seal between said rotor and said casing and means for discharging the fluid entering said seal into said nozzle.

11. In an elastic fluid turbine, a casing, a 90 rotor, alternate rows of nozzles and vanes, fluid seals mounted between said casing and said rotor and means for discharging the fluid leakage entering said seals into said nozzles.

95

12. In an elastic fluid turbine, a casing, a 100 rotor, alternate rows of nozzles and vanes, an interleaving seal between said casing and said rotor, and a passage between said seal and said nozzles whereby the fluid leakage entering said seal is delivered to said nozzles.

13. In an elastic fluid turbine, a stationary casing provided with directing vanes, a rotor provided with reaction nozzles which alternate with said directing vanes, an interleaving seal between said rotor nozzles and the inner peripheral face of said casing and fluid passages located between the leaves of said seal and communicating with said nozzles.

105

14. In an elastic fluid turbine, agents, 110 wherein the motive fluid in its course therethrough gives up a portion of its energy by impulse, a plurality of rows of moving agents whereby the fluid pressure is converted into velocity and said velocity abstracted, a plurality of rows of stationary agents alternating with said rows of moving agents, whereby, without creating pressure drops, the angularity of the fluid stream is changed.

115

15. In an elastic fluid turbine, nozzles whereby a portion of the fluid pressure is converted into velocity, a row of movable members absorbing such velocity, a rotatable collecting chamber for the motive fluid issuing from said members, instrumentalities whereby the fluid issuing from said collecting chamber has a portion of its pressure converted into velocity and abstracted and a plurality of alternate annular rows of moving 125

120

130

- nozzles and stationary elements whereby the fluid, after having its velocity abstracted, is fractionally expanded and the resultant available energy is converted into rotary motion.
16. In an elastic fluid turbine, a casing provided with inwardly discharging nozzles whereby a portion of the thermal energy of the working fluid in the same is converted into kinetic energy in the form of velocity, a rotor, impulse blades on said rotor and formed so that the energy due to said velocity is absorbed without further expansion, a chamber receiving the motive fluid from said blades and forming a collecting chamber, alternate rows of reaction nozzles and directing vanes receiving fluid from said rotor chamber.
17. In an elastic fluid turbine, a casing provided with fluid nozzles whereby a portion of the thermal energy of the working fluid entering the same is converted into kinetic energy in the form of velocity, a rotor, agents carried by the rotor for abstracting the energy rendered available by said nozzles, a chamber formed in said rotor receiving fluid from said agent and alternate rows of reaction nozzles and directing vanes receiving fluid from said chamber.
18. In an elastic fluid turbine, a rotor provided with a plurality of rows of working elements wherein the motive fluid gives up a portion of its energy by reaction, a casing provided with a plurality of rows of fluid directing elements, a shroud for each of the working elements, and an interleaving seal between said shroud and said casing.
19. In an elastic fluid turbine, a casing, a rotor provided with a plurality of working elements adapted to abstract energy from the motive fluid by reaction, fluid seals between said rotor and said casing, and means for discharging fluid entering said seals into said working elements.
20. In an elastic fluid turbine, a casing, a rotor provided with a plurality of working elements arranged in an annular row and adapted to abstract energy from the motive fluid by reaction, a shroud for said elements, and a fluid seal between said shroud and said casing.
21. In an elastic fluid turbine, a rotor comprising two cylindrical portions provided with undercut slots, which are formed in their peripheral faces, a ring provided with a plurality of working agents located in each of said slots, a key ring for securing each of said rings in place in said slots, and means for locking all of said rings together.
- In testimony whereof, I have hereunto subscribed my name this 20th day of September, 1904.

GEO. WESTINGHOUSE.
